GREGG E. SAWYER AND JOHN W. SMITH, OF INDEPENDENCE, KANSAS

WELL BORING, SPUDDING, AND BAILING APPARATUS

Application filed February 25, 1928. Serial No. 256,952.

This invention relates to well boring, spudding, and bailing apparatus, and more particularly to an improved combined spudding reel drum, bailing reel drum, spudding mechanism and means for operating said parts.

An object of this invention is to provide a spudding or drilling reel drum, a bailing reel drum and a spudding attachment, and also convenient, simple means for applying power to said parts from a common source, all of a simple, durable and inexpensive character, compactly arranged and adapted to facilitate efficient co-operation.

A further object being to provide a spudding attachment that may be quickly and readily connected with or disconnected from the driving mechanism, to permit its operation independently of the spudding and bailing reels.

Another object of this invention is to provide means whereby the spudding operation, which prepares the contents of the well for bailing, may be promptly followed by said bailing operation, thereby avoiding the usual delay, and loss of the effect of the spudding.

A further object being to provide a spudding attachment, so located and arranged as to permit its prompt application to the spudding or drill tool line, and operation through the same driving means that operates the spudding line drum.

A further object being to provide simple, common driving means for the spudding and bailing reels, of such a character as will insure against simultaneous operation of said parts, yet of such a construction as to permit the drive or release of either reel, immediately, without affecting the other.

These and other objects will appear in the following specification and be finally pointed out in the appended claims, it being understood that slight changes in form and minor details of construction may be resorted to without departing from the spirit of this invention.

Similar numerals indicate corresponding parts in all the figures of the drawings in which

Fig. 1 is an elevation of a well cleaning ap-

paratus constructed in accordance with this invention.

Fig. 2 is a side view showing in dotted lines the swing of the rocker arm and spudder arm.

Fig. 3 is a detail section on line 3—3 of Fig. 1.

Figs. 4 and 5 are details of the rocker arm and spudder arm respectively.

By reference to the drawings, it will be noted that the detail manner of mounting the parts has not been shown, it being understood that while uprights 1 forming a part of the usual tower, appear in the drawings, it will be obvious that if greater portability is desired, appropriate uprights adapted to support the parts may be permanently or removably mounted on the front or rear of a motor vehicle (not shown) or in any manner, required by conditions.

Under the old practice a well is drilled by a tool suspended at the lower end of a line, secured at its upper end to a rocker beam adapted to lift and drop the tool.

If a well becomes clogged up, or for any reason requires cleaning out, after arranging the necessary mechanism including a spudding reel and other parts above the well, a spudding tool, having considerable weight, is secured at the end of a line, and lowered into the well. Said spudding tool is adapted to be raised and lowered to mix the liquid and solids in such a manner as will permit the bailing operation.

The manner of lifting and lowering the tools during drilling or spudding has been very objectionable, and especially so in spudding. Said old method consists of jerking the tool up and letting it drop, causing severe and damaging jar to the mechanism and frequent breaking of the line, causing delay and expense, as well as requiring a much heavier and more expensive line than is required with this improved attachment.

After the spudding has been performed, it has been the practice, to raise the spudding tool, remove said tool from the end of the line, attach the bailer and lower same into the well for its usual purpose. In other instances the bailing tool, which requires a much lighter

100

line than the spudder, is operated from some inconvenient position, or adjustment of the machine must be made to bring the bailing reel and other parts into a position to properly function.

All of the above objectionable features and others, experienced with other mechanisms are overcome in the present invention.

On uprights 1 a power shaft 2 is mounted for rotary movement, in bearings 3.

On shaft 2 are loosely mounted a spudding reel 4 and a bailing reel 5.

The spudding reel consists of the drum 6, having the usual end flange 7 and a brake drum 8, on which is mounted band brake member 9, provided with brake applying lever 10 mounted in any preferred manner, convenient to the operator's hand or foot as required. The spudding reel is loosely mounted on shaft 2 and is provided with a clutch member 11 adapted to mesh with a clutch, which will be described later.

The bailing reel consists of the drum 12 having the usual end flange 13 and a brake drum 14, on which brake band 15 operates. Brake applying lever 16, being mounted in any preferred manner convenient to the operator. The bailing reel is loosely mounted on shaft 2 and is provided with a clutch member 17 on the end of said reel adjacent to the spudding reel.

On power shaft 2, between the adjacent ends of the spudding and bailing reels, each being provided with clutch members 11 and 17 respectively, is splined a gear 18, adapted to be driven by a preferred form of motive power (not shown). Integral with gear 18 is a double faced clutch provided with clutch members 19 and 20 adapted to engage the clutch members 11 of the spudding reel or 17 of the bailing reel, or rotate free of both, its movement being accomplished by clutch lever 34 operating in the usual groove 35 in the clutch, and pivotally mounted in any preferred manner.

The spudding mechanism consists of a crank arm 22 rigidly mounted on the power shaft 2. A rocker shaft 23 is mounted in this instance in bearings 24 on the uprights 1, and is provided at its end with a rocker arm 25, in which a bearing slot 26 is provided. A sliding bearing block 27 in which bearing pin 28 operates, is mounted to slide in slot 26, pin 28 being mounted in one of a series of openings 29 near the end of crank arm 15.

A spudder arm 30 is rigidly mounted on rocker shaft 23 and is provided with a pulley 31 rotatably mounted on stud 32 carried in one of a series of openings near the free end 60 of the spudder arm.

Loosely mounted for both rotary and longitudinal movement on shaft 23 is a pulley 33.

A spudding line must be of greater strength than the bailing line while a short portion of 65 said spudding line is shown on the drawings,

their relative weight and thickness is indicated by the size of the reels 6 and 12.

From the above, the operation will be obvious. When a well is to be cleaned, a spudding tool (not shown) attached to the end of a spudding line wound on spudding reel 6, and running over pulley 33 and a pulley (not shown) arranged directly above the well, is lowered into the well by gravity, reel 6 being free of the clutch, and its speed controlled by brake lever 10.

When the spudding tool is at the proper depth, the spudding line is taken from pulley 33 and is brought into engagement with pulley 31 on spudding arm 30.

Pin 28 is passed through one of the openings 29, into block 27 as shown, and rotary movement is applied through gear 18 to shaft 2, which causes crank arm 22 to rotate and swing rocker arm 25 and spudder arm 30.

The spudding line which is in engagement with pulley 31 with one end held on reel 6 will cause a drawing up and lowering of the spudding tool in the well and a very effective spudding operation.

It will be noted that the limit of movement of the arm 30 is approached in a manner to insure the stopping and starting of the tool in such a manner as to avoid all jar to the parts.

When the spudding has been completed, the spudding line is shifted from pulley 31 to pulley 33, pin 28 connecting crank arm 15 and rocker arm 25 is withdrawn, clutch member 19 is brought into engagement with clutch member 11 on reel 6 and the spudding tool is quickly brought to the surface.

Immediately upon the removal of the spudding tool from the well the bailing tool is dropped by gravity under control of brake lever 16 into the well, said latter operation being so promptly accomplished, that the minimum amount of settling of the muddy mixture in the well is permitted.

Having described the invention, what is claimed and desired to be secured by Letters Patent is:

1. A device of the class described, comprising a power shaft, a spudding reel adapted to receive a spudding tool line, a bailing reel adapted to receive a bailing tool line mounted on said power shaft, shiftable means on the shaft and interposed between said reels, for driving the power shaft including common means for transferring power from the power shaft to either of said reels, and means moved by the operator for shifting the last mentioned means.

2. A device of the class described, comprising a power shaft, a spudding reel adapted to receive a spudding tool line, a bailing reel adapted to receive a bailing tool line each loosely mounted for independent movement on said power shaft, means for controlling said independent movement, a shiftable

member on said shaft for driving the power shaft, common means forming part of said member for transferring power from the power shaft to either of said reels, and means moved by the operator for shifting the last mentioned means.

3. A device of the class described, comprising a power shaft, a spudding reel adapted to receive a spudding tool line loosely mounted for independent movement on said power shaft and a brake for controlling said independent movement, a bailing reel adapted to receive a bailing tool line loosely mounted for independent movement on said power shaft and a brake for controlling said independent movement, shiftable means on the shaft and interposed between the reels, for driving the power shaft including common means for transferring power from the power shaft to either of said reels, and means moved by the operator for shifting the last mentioned means.

4. A device of the class described comprising a power shaft, a spudding reel loosely mounted for independent movement on the power shaft having a clutch member, a bailing reel loosely mounted for independent movement on the power shaft having a clutch member, a driven gear splined on the power shaft having clutch members adapted to engage either the spudding reel or the bailing reel, and operate said shaft independently of both reels, means moved by the operator for shifting said driven gear toward or away from either one of said reels, and means for controlling said independent movements of the spudding and bailing reels, substantially as described.

5. A device of the class described including a power shaft, a spudding reel adapted to receive a spudding tool line, loosely mounted for independent movement on the power shaft and having a clutch member, a bailing reel adapted to receive a bailing line, loosely mounted for independent movement on the power shaft and having a clutch member, a driven gear splined on the power shaft between said reels having clutch members adapted to rotate the shaft independently of said reels and be brought into engagement with either of said reels, and a spudding device operated by said power shaft adapted to engage the spudding tool line.

6. A device of the class described including a power shaft, a spudding reel adapted to receive a spudding tool line, loosely mounted for independent movement on the power shaft and having a clutch member, a bailing reel adapted to receive a bailing line, loosely mounted for independent movement on the power shaft, a driven gear splined on the power shaft, and having clutch members, said gear being adapted to rotate the shaft independently of said reels and be brought into engagement with either of said reels

and a spudding device comprising a rocker shaft, a spudder arm mounted on the rocker shaft having a roller adapted to engage the spudding line, a rocker arm mounted on the rocker shaft, and a crank arm mounted on the power shaft in engagement with said rocker arm, adapted to rock said parts and apply a spudding movement to said line.

7. A device of the class described including a power shaft, a spudding reel adapted to receive a spudding tool line, loosely mounted for independent movement on the power shaft and having a clutch member, a bailing reel adapted to receive a bailing line, loosely mounted for independent movement on the power shaft and having a clutch member, a driven gear splined on the power shaft having clutch members, and adapted to rotate the shaft independently of said reels and be brought into engagement with either of said reels and a spudding device comprising a rocker shaft, a spudder arm mounted on the rocker shaft, having a roller adapted to engage the spudding line, a rocker arm mounted on the rocker shaft having a traveling bearing block mounted in a slot therein, a crank arm mounted at the end of the power shaft having a bearing pin at its outer end, adapted to engage said bearing block, all adapted, when the power shaft is rotated, to impart a rocking movement to the spudder arm and spudding movement to said spudding line.

8. A device of the class described, including a power shaft, a spudding reel adapted to receive a spudding tool line loosely mounted for independent movement on the power shaft, means for clutching the reel to said shaft when desired, a second shaft, means for moving the second shaft from the power shaft, a projecting member fast on the second shaft, an anti-friction guide mounted on the last mentioned member and spaced from the second shaft, and a spudding tool line engaging said guide and having one of its ends anchored to said reel, the shafts being so arranged relatively to one another that the second shaft, in operating, will cause the guide to move the spudding line back and forth toward and away from the second shaft.

9. In a well rig, a power shaft, a spudding reel mounted on said shaft and adapted to receive a spudding tool line, a bailing reel mounted on said shaft and adapted to receive a bailing tool line, means on the shaft and arranged between said reels for driving said power shaft, common means forming part of the last mentioned means for transferring power from the power shaft to either of said reels, and means moved by the operator for shifting the first mentioned means.

10. In a well ring, a power shaft, a spudding reel mounted on said shaft and adapted to receive a spudding tool line, a smaller

bailing reel mounted on said shaft and adapted to receive a bailing tool line, means on the shaft and arranged between said reels, for driving the power shaft and including means for transferring power from said shaft to either of said reels, and a lever engaging the first mentioned means and arranged to be moved by the operator.

11. In a well rig, a power shaft, a spudding reel adapted to receive a spudding tool line, loosely mounted for independent movement on said shaft, means for holding said reel stationary while the shaft is rotated, a bailing reel adapted to receive a bailing tool line and loosely mounted for independent movement on said shaft, means adapted to be actuated by the operator for holding the bailing reel stationary while the shaft is rotating, shiftable means on the shaft interposed between said reels for driving the power shaft including means for transferring power from the power shaft to either of said reels, and manually operated means for shifting the last mentioned means.

12. In a well rig, a rotatable power shaft, a spudding reel and a smaller bailing reel loosely mounted on said shaft; clutch means moved by the operator for clutching either of said reels to the shaft, a rock shaft, means including connected elements for causing the rock shaft to be actuated by the power shaft, said elements being detachably connected to permit the power shaft to operate independently of the rock shaft, a member fixed to and projecting from the rock shaft and arranged adjacent to the spudding reel, a guide mounted on said member and spaced from the rock shaft, and a spudding tool line engaging said guide and having one of its ends secured to the spudding reel.

13. In a well rig, a horizontally disposed rotatable power shaft, a spudding reel loosely mounted on said shaft, a clutch mechanism for fixedly connecting the reel to the shaft when desired, a brake for the reel adapted to be controlled by the operator, a horizontally disposed rock shaft mounted above the power shaft, means actuated by the rotation of the power shaft for rocking the rock shaft, said last mentioned means including elements adapted to be disconnected when it is desired for the power shaft to rotate while the rock shaft remains stationary, an arm fixed to the rock shaft, a guide roller carried by said arm, and a spudding reel line engaging said roller and having one of its ends fixed to said reel.

14. In a well rig, a rotatable power shaft, a spudding reel, a bailing reel, power transmitting means including clutch elements moved by the operator for clutching either of said reels to the shaft, a rock shaft, means including connected elements for causing the rock shaft to be actuated by the power shaft, said last mentioned means also permitting the power shaft to operate independently of the

rock shaft, a member fixed to and projecting from the rock shaft and arranged adjacent to the spudding reel, a guide mounted on said member and spaced from the rock shaft, and a spudding tool line wound on the spudding reel and engaging said guide.

15. A device of the class described, including a power shaft, a spudding reel adapted to receive a spudding tool line, said shaft being rotatable independently of said reel, means for clutching the reel to said shaft when desired, a second shaft, means for moving the second shaft from the power shaft, a projecting member fast on the second shaft, an anti-friction guide mounted on the last mentioned member and spaced from the second shaft, and a spudding tool line wound on the spudding reel and engaging said guide, the shafts being so arranged relatively to one another that the second shaft, in operating, will cause the guide to move the spudding line back and forth toward and away from the second shaft.

16. In a well rig, a rotatable shaft, a spudding reel loosely mounted on the shaft, a bailing reel loosely mounted on the shaft, means for driving the shaft and said reels, said means including clutch elements controlled by the operator for rotating either reel independently of the other, a rock shaft, means for driving the rock shaft from the first mentioned shaft, a member fixed to and projecting from the rock shaft and arranged adjacent to one of said reels, a guide mounted on said member and spaced from the rock shaft, and a tool line wound on one of said reels and engaging said guide.

17. In a well rig, independently rotatable spudding and bailing reels, a rotatable shaft on which the reels are loosely mounted, power transmission means for rotating the shaft and reels, and including clutches controlled by the operator for driving either reel independently of the other, a brake for each reel controlled by the operator, a rock shaft arranged above the rotatable shaft, a second power transmission means for driving the rock shaft from the rotatable shaft, one of said power transmission means including connected elements capable of disconnection to allow the reels to rotate while the rock shaft is idle, a projecting member fast on the rock shaft, an anti-friction guide mounted on the last mentioned member and spaced from the second shaft, and a tool line wound on one of said reels and engaging said guide, the shafts being so arranged relatively to one another that the rock shaft, in operating, will cause the guide to move the spudding line back and forth toward and away from the second shaft.
